United States Patent Office.

J. E. PENCILLE, OF LOCKPORT, NEW YORK.

Letters Patent No. 92,643, dated July 13, 1869.

IMPROVED BEDSTEAD.

The Schedule referred to in these Letters Patent and making part of the same.

To all whom it may concern:

Be it known that I, J. E. PENCILLE, of Lockport, in the county of Niagara, and State of New York, have invented certain new and useful Improvements in Bedsteads; and I do hereby declare that the following is a full and exact description thereof, reference being had to the accompanying drawings, making part of this specification.

Figure 1 is a plan of my improved bedstead.

Figures 2 and 3 are detail views.

Like letters of reference indicate corresponding parts in all the figures.

The novelty in my invention consists in connecting the ends and the body of the bedstead in whole sections, constituting three parts, and connecting these parts by hand-screws and nuts, as hereinafter set forth.

In the accompanying drawings—

A A indicate the end-sections, made up of the ordinary posts, f f, and cross-boards, k k, rigidly secured together to form a whole; and

B, the body or central portion of the bedstead, consisting of the ordinary side-boards, p p, held fast by means of cross-bars, s s.

The ends of the side-boards have tenons, a a, which rest in corresponding mortises, b b, of the posts.

Through the cross-bars s s pass hand-screws, d d, which screw into nuts g g, in the cross-boards k k, thereby drawing the parts firmly together, and producing tight joints.

This device for connecting and securing the parts is not only very simple, cheap, and effective, and is easily put together and taken apart, but it also admits of the end and body-sections being made entire, and the parts composing them secured permanently together, without further attachment. The great advantage of this

method of connection, where there are but three several parts, is apparent over the ordinary method, where the side-boards or end parts are separate, and have to be put up in pieces.

The nuts g g fit loosely in corresponding sockets in the end-sections A, and are made removable. By this means, the nuts may be made of more durable material than if they were formed in the sections A A themselves, and they can be replaced with new ones if they become worn or defective. They also adapt themselves to any position, whether angularly or otherwise, as the screws draw up, thereby obviating difficulty from shrinkage, or from a careless fit of the screws, in this manner obviating the necessity of great nicety in adapting the screws and nuts.

I am aware that a spring-bed bottom has been used which is made separate from the side-rails and end portions of the bedstead, and secured to the latter by screws; I am also aware that a bed-screw has been arranged to work through a rigid transverse screw-nut; but as they form no part of my invention, I do not wish to claim them.

What I claim as my invention, and desire to secure by Letters Patent, is—

The removable nuts g, formed each with an internal longitudinal screw-thread, and made plain on the outside, when used in connection with the cross-pieces k s, and screws d, and so fitted as to adapt themselves to the position of the screws, as herein set forth.

In witness whereof, I have hereunto signed my name, in the presence of two subscribing witnesses.

J. E. PENCILLE.
